METHOD AND APPARATUS FOR WRAPPING BOXES

Gideon R. Kreider, Jr., Lebanon, Pa.

Application July 29, 1932, Serial No. 625,584

37 Claims. (Cl. 93—54)

This invention relates to a method and apparatus for making boxes, and more particularly to an improved method and apparatus for assembling and wrapping paperboard boxes of round, rectangular, polygonal, concave, convex or any other regular or irregular shape or contour.

It has heretofore been considered impossible to assemble and wrap boxes which have side walls which are cylindrical, elliptical, concave, convex, heart-shaped, or of irregular shape and contour automatically on a wrapping machine. No method of assembling such boxes has heretofore been devised which could be efficiently and effectively executed by machine, and no machine or apparatus for carrying out the same has been devised. Such boxes have heretofore been made only by hand with the aid of simple hand tools. Such boxes have consequently been very expensive as compared with the regular, straight sided, rectangular boxes wrapped automatically by machine.

Paperboard boxes heretofore made having upwardly or downwardly extending rims have also been largely hand made. And while they are attractive and desirable, they have been used very little except for expensive packaging, since the cost of these hand made boxes has been prohibitive.

Also, irregular shaped boxes having padded tops or bottoms have heretofore been made by hand, which has made them so costly that they have only been used in limited quantities for the packaging of expensive articles.

It is an object of this invention to provide a method of making paperboard boxes of regular or irregular outline, with speed and efficiency and with economy as to materials and labor.

It is another object of this invention to provide an apparatus for making paperboard boxes of irregular contour automatically.

Still another object of this invention is to provide apparatus which may be attached to wrapping machines in common use and which will operate in conjunction therewith to wrap boxes of regular or irregular shape and contour with speed, efficiency and economy.

Another object of this invention is to provide apparatus which may be attached to wrapping machines in common use and which operates in conjunction therewith to assemble boxes and box covers having vertically extending side flanges or rims.

Still another object of my invention is to devise a method and provide apparatus for auto-

matically padding and wrapping boxes of irregular shape and contour.

Another object of this invention is to provide an attachment adapted to be applied to box making and wrapping machines in common use, which can be easily and quickly connected to such machines, which operates in perfect synchronism therewith, which is sturdy, strong and lasting in construction, substantially foolproof in operation, and which is relatively inexpensive to make and may be operated as fast as the machine to which it is attached will operate.

Other objects of this invention will become apparent as the disclosure proceeds.

In accordance with this invention, boxes having side walls of irregular contour, such as cylindrical, elliptical, oval, heart-shaped, polygonal, concave, convex, and boxes with round or irregular shaped corners may be wrapped quickly, efficiently, effectively and economically by machine. The invention comprehends apparatus which may be attached to well known wrapping machines.

A pressure block, shaped to fit the inside of the container of the box to be wrapped, is attached to the operating head of the wrapping machine. If the box to be made has a flat bottom, the vertically reciprocating platform upon which the box rests may be provided with a flat top surface. A wrap is provided, the outer edge of which is slit so as to provide a plurality of tabs which extend up over the side walls of the box when the same is wrapped. The wrap is then glued, the box bottom inserted into the continuous side wall, and the side wall and bottom is positioned on the wrap so that the lower edge of the side wall adheres thereto. The box side wall, with the wrap adhering thereto, is then telescoped over the pressure block, spring fingers being provided which hold the same in place.

When the machine is operated the pressure block carrying the unassembled box moves downwardly and seats upon the reciprocating platform, pressing the box bottom into place against the wrap sheet. The platform and pressure block then move downwardly, and during this movement, the outer tab portions of the wrap come into contact with a series of brushes, which are arranged to surround the box. The brushes wipe the tab portions of the wrap upwardly into contact with the side walls of the box. When the box to be wrapped has cylindrical, concave, convex, heart-shaped or generally irregular shaped side walls, it is preferable to arrange the brushes in inclined position so that the tab portions of

the wrap are successively and progressively wiped into contact with the side walls of the box. By this arrangement of the brushes, the tab portions of the wrap are arranged so as to overlap one another, and a smooth and finished appearing box results. As the box continues its downward movement, pressure blocks move inwardly to press the tab portions of the wrap firmly against the side portions of the box, firmly cementing the same together. The box is then ejected from the machine and a side wall strip is applied to the box wall, which overlaps the tab portions and folds over the upper edge of the box. By providing flap folding brushes and folding blocks of the proper shape and arrangement, any desired shape of box may be assembled and wrapped.

If a box having a vertically extending rim portion is desired, the vertically moving platform 20 of the machine is provided with a top surface having a raised portion which extends above the rim thereof. The pressure block is provided with a plate mounted thereon which is adapted to overhang and engage the upper edge of the side wall of the box and telescope the same over the raised portion of the platform. The wrap then extends over the raised portion of the platform and downwardly around the depressed rim portion thereof so as to provide the container with an inset bottom. The tab portions surrounding the wrap are then folded upwardly by the brushes and pressed against the side walls of the box by the pressure blocks as above described.

In forming boxes with padded bottoms, the 35 padding is placed on the glued wrap sheet which is positioned to adhere to the lower edge of the box side wall. The surface of the vertically moving platform is suitably hollowed or concaved to conform with the desired shape of the padding. Preferably the outer area of the bottom wall is not padded. This permits the wrap sheet 40 to adhere directly to the bottom wall of the box around the padded area, and makes a stronger box. This is accomplished by providing the platform with a raised rim portion which surrounds the concaved area.

Where the word "box" is used in the specification and claims, it is understood that either the containing part and/or the cover part of a container is meant, and the same should be so construed.

Although the novel features which are believed to be characteristic of this invention will be particularly pointed out in the claims appended hereunto, the invention itself, as to its objects and advantages, and the manner in which it may be carried out, may be better understood by referring to the following description taken in connection with the accompanying drawings forming a part thereof, in which

Fig. 1 is a side elevational view of a wrapping machine with the box forming apparatus herein disclosed attached thereto, certain parts being shown in cross section to more fully illustrate 65 certain features of the construction;

Fig. 2 is a vertical fragmentary cross sectional view through the apparatus, showing more particularly the pressure block and a box in the process of being wrapped in position thereon;

Fig. 3 is an elevational view of the reciprocating platform of the machine;

Fig. 4 is a cross sectional view of the pressure block and reciprocating platform as they appear at one stage of the box forming operation;

Fig. 5 is a vertical cross sectional view through

the pressure block, reciprocating platform and wiping brushes, as they appear at another stage in the box forming operation;

Fig. 6 is a side view of the pressure block and clamping arrangement as they appear at a further step in the box forming operation;

Fig. 7 is a top view of the pressure block and associated pressure and guiding plate, this view being taken on line 7-7 of Fig. 4;

Fig. 8 is a horizontal top view of the brush structure showing the arrangement of the brushes and associated manipulating devices for wrapping a cylindrical box;

Fig. 9 is a horizontal top view of the clamping blocks with a cylindrical box positioned therebetween, this view being taken on line 9-9 of Fig. 6;

Fig. 23 is a top view of a heart-shaped container provided with a box cover having an upstanding rim and a padded top;

Fig. 24 is a top view of a box having rounded corners, the spring fingers of the wrapping machine being shown associated therewith; and

Fig. 25 is a top view of a box having concave side walls and more particularly illustrating the various shapes and forms of boxes which may be wrapped by the method and apparatus herein disclosed, the spring fingers of the apparatus being arranged to wrap this type of box.

Similar reference characters refer to similar

parts throughout the several views of the drawings.

There is shown in Fig. 1 a box wrapping machine having the novel box wrapping attachment 5 associated therewith. The machine generally comprises a table 1 supported by legs 2. A vertical extending drive shaft 3 extends through the table 1 and is supported at the lower end thereof by a thrust bearing mounted on the platform 4. The drive shaft 3 extends through a standard or gooseneck 5, resting on the table 1 of the machine. The drive shaft 3 is rotated by a suitable power source, such as a motor, connected to the shaft through a pulley wheel 6 and suitable connections. A clutch 7 controlled by a foot lever 8 is provided which may be actuated to throw the machine into and out of operation. Another foot lever 9 is effective for stopping the machine at any time.

20 A cam member 10 in the form of a cylindrical drum is mounted on the lower end of the shaft 3. The drum 10 is connected to operate the lower forming block 50 of the machine, as will hereinafter be described. An operating drum 11 is mounted on the upper end of the shaft 3 and is operative to manipulate a main lever 12 pivotally mounted by means of a pivot 13 on the arm 14 of the gooseneck 5. The lever 12 is provided with a roller 15 mounted on the mid section thereof which rolls within the cam track 16 provided in the cam drum 11.

A pair of bracket arms 17 extend from the gooseneck 5 and support a pair of guide members 18. A plunger 19 reciprocates between the guide members 18 and carries the upper form block 40 at the lower end thereof. One end of the lever 12 is operatively connected to the plunger 19 by means of a connecting link 20 pivotally secured to the plunger 19 by means of a stud 21. To permit adjustment between the lever 12 and connecting link 20 an elongated slot 22 is provided in the link into which a stud 23, provided on the end of the lever, extends. The connection between the lever 12 and the link 20 may then be adjusted as operating conditions require by means of an adjusting screw 24. A counter weight 25 is attached to the other end of the lever 12 to balance the operation of the machine. Upper form block 40 is mounted on a tenon 26 secured to the end of the plunger 19, as shown in Figs. 1 and 2. The upper form block 40 and its various attachments constitute an important feature of this invention, as will be described more in detail hereinafter.

55 Means are provided for stripping the finished box from the upper form block 40. A lever 27, supported by an arm 28, which branches upwardly from the gooseneck 5, is provided at one end with a roller 29 which rolls within a secondary cam track 30 provided in the upper drum. A connecting link 31 connects the free end of the lever 27 to a yoke 32. The yoke 32 carries the stripper fingers 33, which at predetermined times, pass through aligned apertures in the upper form block 40 to strip the wrapped box B therefrom. The stripper fingers 33 are guided in their vertical reciprocating movement by means of a pair of guide rods 34, which are secured to the yoke 32 and are adapted to slide within a pair of guide lugs 35 suitably secured to the stationary guides 18. The cam slot 30 is so shaped as to manipulate the stripper fingers 33 in the proper manner when the machine is in operation.

75 A platform or lower form block 50 is mounted

on the upper end of a hollow tube 51 adapted to telescope within a post member 52 which rests upon the base 53, formed in the frame-work of the machine. A suitable coupling connection 54 is provided to permit the lower form block 50 to be removed from the supporting tube 51.

A coil spring 45 is positioned within the hollow tube 51 and normally holds the form block 50 in raised position. The upper forming block 40 is arranged to seat on the lower form block 50 with the box bottom and its adhering wrapper confined therebetween. The lower form block is forced downwardly against the action of the spring 45 at predetermined intervals during which the wiping brushes 60 and the presser members 90 come into play.

The wiping brushes 60 and the pressure members 90, which will be described more in detail hereinafter, are manipulated by means of mechanism operatively connected to the shaft 3. A 20 roller 61 carried on one end of the lever 62 rolls in the cam track 63 provided in the lower cam drum 10. The lever 62 is pivotally mounted intermediate its ends to an arm 64 supported by the platform 4. A link 65 is pivotally connected 25 to the other end of the lever 62 and to a movable sleeve 66 surrounding the tube 51. The sleeve 66 is provided with a plurality of radiating arms 67. Four arms, equally spaced, are shown in the drawings for purposes of illustration, but the number of arms used and the angular position thereof will depend somewhat upon the shape of the box to be wrapped.

Each arm 67 carries a rod 68 having a stud 69 extending upwardly from the end thereof. The 35 studs 69 each reciprocate in a bearing 70 formed as a part of an extension 71 projecting from the slide 72. A link 73 is pivotally connected to each of the studs 69 and a cam 74.

The cam 74, pivoted about the point 75, is provided with a stud 76 adapted to engage the hooked end of a member 77 to rock the wiping brush 60 upwardly out of operative position. Each of the wiping brushes comprises, generally, a brush block 78 to which a plurality of rows 45 of brush bristles 79 are fastened. The brush blocks 78 are each secured to a suitable frame 80 mounted to pivot about a horizontal rod 81 rotatably mounted in a pair of brackets 82. The hooked member 77 is connected to the rod 81 50 by means of a forked member 83 which is fixed to the rod and pivotally connected to the hooked member 77. The brackets 82 may be of different heights or the slides 72 positioned at different elevations so as to support the various brushes 55 60 at different convenient elevations. The vertical spacing between the upper and lower brushes may be further augmented by mounting the brushes above (see lower brush in Fig. 5) or below (see upper brush in Fig. 5) the supporting 60 frames 80. The proper spacing of the brushes to most effectively wrap the selected box may thus be attained. The brackets 82 are each supported by one of the slides 72 which may be moved inwardly or outwardly and then held in 65 this position by adjusting the clamping handle 99. The brushes 60 may thus be spaced any distance apart to accommodate the cross section dimensions of the box to be wrapped.

The studs 69 are also adjustable on the rods 70 68 to accommodate the brush tilting mechanism and pressure block operating mechanism to the cross sectional dimension of the box.

In operation, when the arms 67 are drawn downwardly, the cams 74 are rocked to draw the 75

hook 77 downward, causing the brush blocks 60 to swing or pivot from substantially horizontal position to substantially vertical position. The blocks are thus moved out of the way, permitting the box to move upward out of the machine after the wrapping operation. The brush blocks 60 will drop back into horizontal position by gravity when the arms 67 move upward.

The brushes 60 are adapted to wipe the glued flaps 100 of the box wrap 101 against the side walls 102 of the box B under construction. The upper forming block 40, carrying the box wrap 101, the side walls 102 and the box bottom 103, moves downwardly until it seats against the lower forming block 50. Both the upper block 40 and lower block 50 then move down through the brushes 60 which operate to wipe the glued flaps 100 into adhesive contact against the side walls 102 of the box under construction. This operation will be described more in detail hereinafter.

After the box has moved through the brushes 60 the clamping blocks 90 move inwardly and press the flaps 100 of the wrap sheet against the side walls 102 of the box, causing the flaps firmly to adhere to the box wall. The clamping blocks 90 are of the proper shape to completely surround the box side wall. Any convenient number of clamping blocks may be used. Each clamping block 90 is supported in a seating member 91 which, in turn, is supported by one or more rods 92, horizontally slidable within a bracket 93 projecting downwardly from the slide 72. Each of the cams 74 is provided with a high point lug 94 being effective to press against a button 95 projecting from each clamping block 90, thus forcing the blocks 90 inwardly into clamping engagement with the box side walls. A coil spring 96 may be provided to return the clamping blocks to normal position when the pressure has been removed.

At the conclusion of the wrapping operation, the upper forming block 40 moves upwardly carrying the wrapped box with it. The sleeve 66 is drawn downwardly rocking the cams 74 and tilting the brushes 60 so as to permit the wrapped box to pass freely therethrough. The stripping fingers 33 then come into play to strip the wrapped box off from the upper forming block 40, permitting the box to drop to resting position on the lower pressure block 50. The ejector 99 then operates to push the box off the lower pressure block.

The particular construction and assembly of the attachments for wrapping irregularly shaped boxes will now be described.

In the formation of boxes having a vertically extending rim portion, a lower platform or pressure block 50 of the general shape shown in Figures 3 to 6, inclusive, is provided. This platform is provided with a raised portion 151 in the center thereof and a recessed rim portion 152 surrounding the raised portion 151. The raised portion 151 is of such form and shape as to receive the lower end of the side walls 102 of the box under construction.

The upper pressure block 40 is provided with a plate member 161 mounted on the top thereof. The plate member has a central aperture 162 cut therein through which the tenon 26 of the plunger 19, which supports the pressure block, extends. The plate 161 is supported on a pair of adjustable screws 163 which extend into the block 40. By manipulating the screws 163, a limited vertical adjustment of the plate 161 with reference to the pressure block may be made.

In assembling, for example, a cylindrical box having a vertical extending rim portion, as shown in Figure 13, the bottom wall 103 is inserted within the side walls 102 in any convenient manner. The side walls 102 are then placed in position upon the glued wrap sheet 101 and then pressed together so that the wrap sheet adheres to the bottom edge of the side walls. The side walls 102, with the bottom wall 103 positioned therein and the wrap sheet 101 adhering thereto, is then telescoped over the upper forming block 40, in the manner shown in Figure 2.

A plurality of downwardly projecting spring fingers 164, secured to the plate 161, frictionally engage the side walls 102 and retain the box parts in position on the upper forming block 40. The fingers 164 also prevent the side walls from warping out of shape during the box forming operation. The spring fingers 164 may be provided with upturned ends 165 to facilitate engagement with the side wall portions 102 of the box. These fingers may be positioned in any location where the box side wall would normally be inclined to bulge outwardly away from the form block 40.

As the machine operates, the upper forming block 40 descends with the side and bottom walls, and wrap sheet adhering to the bottom edge of the side wall. When the bottom edge of the box reaches the lower forming block 50, the plate member 161 engages the top edge of the side wall portion 102 of the box and forces the bottom edge of the side wall into position within the surrounding recessed rim portion 152 of the lower forming block 50. The outer portion of the wrap sheet is also carried down so as to seat closely around the recessed rim, and the center portion of the wrap sheet and the bottom wall 103 of the box are pressed together in adhesive relation between the upper forming block 40 and the raised portion 151 of the lower forming block. The box as thus constructed is provided with a vertically extending rim portion, as shown in Figure 13. The vertically extending rim dresses the box up considerably and gives it an attractive appearance.

In wrapping a cylindrical box or a box having arcuate side walls, each brush is preferably positioned in inclined relationship to each of the others, as shown more particularly in Figures 5 and 12. It is found that the best results are obtained when approximately three rows of brush bristles 79 placed in staggered relation are used in each brush.

In wrapping boxes having arcuate side walls, a series of lateral extending cuts 104 defining tabs 100 around the outer edge of the wrap sheet by slitting the edges of the wrap sheet laterally, as shown in Figure 11. During the wrapping operation, bristles 79 of the inclined brushes 60 successively and progressively pick up the tabs 100 and fold them upwardly into adhesive contact against the side wall 102 of the box. This arrangement permits the tabs 100 to shingle or overlap with respect to one another, as shown in Figure 13. An unusually smooth and finished fold is thus secured.

If a box having a vertically extending rim portion is desired, a platform 50 having a raised center portion 151 is used. If a flat bottomed box is desired, a flat surfaced platform 50 is provided, in which case the bottom wall 103 of the box may be positioned so as to abut the lower edge of the box wall, or positioned within the box wall, as desired. If an unusually strong box is desired,

the bottom wall 103 and side walls 102 thereof may be additionally stayed or secured together in any manner before wrapping.

Boxes having padded end walls may also be made with the apparatus herein disclosed. Referring more particularly to Figure 21, a box having a padded end wall is formed by securing the desired padding 106 to the bottom wall 103 of the box. A lower platform or forming block 50, provided with a hollowed-out center portion 153 and a raised intermediate portion 154 of the desired contour, is connected to the reciprocating tube 51 of the machine. The padding 106 is first applied to the bottom wall 103. The side walls 102, with the bottom wall 103 therein, and the wrap sheet adhering thereto, is then telescoped over the upper form block 40 and associated plate 161 then press the bottom edge of the box within the recess 151 causing the wrap to adhere to the inside face of the rim portion, to the edges of the bottom wall 103 and to the padding 106. The wrapping of the box then proceeds as heretofore described.

As a final step in the box forming operation, a wrap strip 107 is applied to the side walls of the box. The wrap strip 107 is a simple strip of paper glued on one side which is wrapped circumferentially around the box in a well known manner.

In addition to boxes having vertically extending rims, and boxes having padded end walls, boxes of every conceivable form and shape may be made by the method and apparatus herein disclosed. By way of illustration, I have shown in Figure 14 a polygonal shaped box in process of formation. The brush members 60 in this case are preferably straight, arranged in horizontal position, relative to the box side walls 110. The tab portions 111 of the wrap sheet may be folded smoothly against the side walls or they may be so cut as to shingle or overlap, as desired.

Heart shaped boxes may also be wrapped by the method and the apparatus herein disclosed. Heart shaped boxes have heretofore required a large amount of hand work to form and wrap the same. In the formation of the heart shaped box by apparatus herein disclosed, a band 120 is provided, which is secured together at the ends thereof to provide a continuous side wall, as shown in Figure 15. A bottom wall 121 of paperboard 50 or other material is inserted within the side wall band 120, the bottom wall 121 spreading the side wall forming band 120 into general heart shaped form, as shown in Figure 18. A bottom wrap 122, shown in Figure 17, is provided with a series of tabs 123 formed by slitting the peripheral edge of the sheet. The slits 124 are preferably cut so that the tabs will shingle or overlap when wrapped around the side walls of the box.

In wrapping a heart shaped box, a heart shaped upper forming block of the proper size is attached to the tenon 26 of plunger 19. Preferably, four brushes, 171, 172, 173 and 174, are used to wipe the tab portions 123 to the side wall 120 of this type of box. Brushes 171 and 172 are so shaped as to conform to and effectively wipe the convex sides of the heart, brush 173 is formed to wipe the point of the heart and brush 174 is shaped to brush the concave end of the heart. One end of each of the brushes 171 and 172 is raised so as to begin the wiping operation near the point of the heart, as shown in Fig. 20. When the convex side walls of the heart have been wiped and the tabs 123 thereto secured in shingled or overlapped relation, brush 174 operates to wipe the concave end of the heart to secure the tabs there-

to. As a final step the inclined brush 173 wipes the point of the heart. The box is finished by applying a glued side wall strip to the side walls of the box in any convenient manner.

In wrapping a heart shaped box, a spring finger 164 secured to the plate 161 should be provided to press the side wall 120 of the box into contact with the concave end of the bottom wall 121 and hold same in this position until the wrap has been fully applied.

To further illustrate the various shaped boxes which may be formed by the method and apparatus herein disclosed, there is shown in Fig. 24 a box of generally rectangular form having a continuous side wall 130 with rounded corners 131. If upper and lower forming blocks 40 and 50, brushes 60 and clamping members 90 of the proper shape and contour are provided, this form of box may be wrapped without difficulty. In all cases, it is preferable to use a spring finger 164 at each point where the side wall of the box is inclined to bulge away from the bottom wall 132.

As a further illustration of the great variety of boxes which may be formed by the method and apparatus disclosed herein, there is shown in Fig. 25 a box having concave side walls 140. To wrap this type of box, an upper forming block having concave side walls, is used. Preferably four brushes of convex contour are used. These brushes are preferably positioned in inclined relation and are attached, as heretofore described, to the moving parts of the machine.

By means of the method and apparatus herein described, a single operator can easily wrap seven hundred irregular shaped boxes per hour. Boxes of any irregular outline can be wrapped by the method and apparatus herein disclosed without difficulty. Furthermore, decorative rims may be formed on the boxes in a large variety and of many different designs. Boxes which have heretofore been only made by hand can thus be produced mechanically at greatly reduced cost.

While certain novel features of the invention have been disclosed and are pointed out in the annexed claims, it will be understood that various omissions, substitutions and changes may be made by those skilled in the art without departing from the spirit of the invention.

What is claimed is:

1. The method of making irregular shaped boxes which includes, providing a wrap sheet, slitting the edges of said sheet to provide tab portions, securing the main portion of said sheet to the box bottom, and progressively securing said tab portion to the side walls of the box in overlapping relationship.

2. The method of making irregular shaped boxes which includes, providing a wrap sheet, slitting the edges of the sheet to provide tab portions, securing the main portion of said sheet to the box bottom, progressively securing said tab portions to the side walls of the box in overlapping relationship, and securing a wrap strip around the side wall of the box.

3. The method of making boxes having side walls of arcuate shape which includes, providing a wrap sheet, slitting the edges of said sheet tangentially to provide tab portions, securing the main portion of said sheet to the box bottom and progressively securing said tab portions to the side walls of the box in overlapping relationship.

4. The method of making boxes which includes, providing a continuous side wall, inserting a bottom wall therein, and securing a wrap sheet

to the bottom wall and the inside edge of the side wall to bind the same together in assembled relationship.

5. The method of making boxes which includes, 5 providing a wrap sheet, a continuous side wall and a bottom wall, inserting the bottom wall into the continuous side wall, securing the central portion of the wrap sheet to the bottom wall and to the inside edge of the side wall so as to provide 10 a box with a vertically extending rim portion, and securing the edges of said sheet to the outside face of the side wall.

6. The method of making boxes which includes, 15 providing a wrap sheet, a continuous side wall and a bottom wall, slitting the edges of the wrap sheet to provide tab portions, inserting the bottom wall into the continuous side wall, securing the main portion of said wrap sheet to the bottom wall and to the inside edge of the side wall 20 so as to provide a box with a vertically extending rim portion, and securing said tab portions to the outside face of the side wall so as to hold the parts together in assembled relationship.

7. The method of making boxes having a vertically extending rim portion which includes, 25 providing a wrap sheet, a continuous side wall and a bottom wall, inserting the bottom wall within the continuous side wall, securing the wrap sheet to the end of the side wall, telescoping said side wall and adhering wrap sheet over a mould, said mould having a raised center portion and a depressed rim portion, and pressing the side wall and bottom wall against said mould so as to cause the wrap sheet to adhere to the bottom wall 30 and inside edge of the side wall of the box.

8. The method of making boxes which includes, 35 providing a wrap sheet, a continuous side wall and a bottom wall, slitting the edges of said sheet to provide tab portions, inserting the bottom wall 40 within said side wall, gluing the wrap sheet to one end of the side wall, telescoping said side wall and adhering wrap sheet over a mould, said mould having a raised center portion and a depressed rim portion, pressing the side wall and bottom wall against said mould so as to cause the wrap sheet to conform to the shape of the mould 45 and to adhere to the bottom wall and the inside edge of the side wall, and wiping said tab portions against the outside face of the side walls so as to cause them to overlap one another and to adhere to the side wall to hold the box parts in assembled set up relationship.

9. The method of making boxes which includes, 50 providing a wrap sheet, a continuous side wall and a bottom wall, slitting the edges of said sheet to provide tab portions, inserting the bottom wall within said side wall, gluing the wrap sheet to one edge of the side wall, telescoping said side wall and adhering wrap sheet over a 55 mould, said mould having a raised center portion and a depressed rim portion, pressing the side wall and bottom wall against said mould so as to cause the wrap sheet to conform to the shape of the mould and to adhere to the bottom wall and the inside edge of the side wall, wiping said tab 60 portions against the outside face of the side walls so as to cause them to overlap one another and to adhere to the side wall to hold the box parts in assembled set up relationship, and securing a 65 wrap strip around the side wall in overlapping relation to said tabs.

10. The method of making padded boxes which 70 includes, providing a wrap sheet, gluing said wrap at selected points to the bottom wall of the box 75 with the padding positioned therebetween, and

gluing the edges of the wrap to the side walls of the box.

11. The method of making irregular shaped boxes with padded end walls which includes, 5 providing a wrap sheet, slitting the edges thereof to provide tab portions, positioning the padding between the sheet and the bottom wall of the box, gluing said sheet to the unpadded portion of the bottom wall of the box so as to cause the same to adhere thereto, and gluing said tab portions 10 to the side walls of the box in overlapping relationship.

12. The method of making boxes having a vertically extending rim portion and a padded end 15 which includes, inserting the bottom wall within the side wall, positioning the padding between said wrap sheet and the bottom wall, and gluing said wrap sheet to the unpadded portions of said bottom wall and to the inside edge of the side wall to hold the box parts in assembled set up 20 relationship.

13. The method of making boxes having a vertically extending rim portion and a padded end 25 which includes, providing a wrap sheet, inserting the bottom wall within the side wall, positioning the padding between said wrap sheet and the bottom wall, and gluing the intermediate portions 30 of said wrap sheet to the unpadded edge portion of the bottom wall and to the inside edge of the side wall, and gluing the edges of said sheet to the outside face of the side wall to hold the box parts in assembled set up relationship.

14. An upper form block adapted to be passed 35 interiorly into a box including a side wall portion shaped to engage the inside face of the box side wall, a portion adapted to extend over and engage the box side wall and means for gripping the box to retain the same in position on said form block.

15. An upper form block adapted to be passed 40 interiorly into a box including side wall portions shaped to conform to the inside face of the side wall of the box, a portion adapted to extend over and engage the box side wall and resilient means for gripping the box to retain the same in position on said form block.

16. Apparatus for wrapping boxes having 45 arcuate side walls, including in combination, an upper form block having side wall portions adapted to fit within the box and shaped to conform to the inside surface of the box side walls, a portion adapted to extend over and engage the box side wall and resilient means for gripping the box side wall to retain the same in position on said form block.

17. Apparatus for wrapping boxes having 50 arcuate side walls including in combination, an upper form block having side wall portions adapted to fit within the box and shaped to conform to the inside surface of the box side walls, a portion adapted to extend over and engage the box side wall and resilient means adapted to press and hold the box side walls in position against the side wall portions of the form block.

18. Apparatus for wrapping boxes having 55 arcuate side walls, including in combination, an upper form block having side wall portions adapted to fit within the box and shaped to conform to the inside surface of the box side 60 walls, a portion adapted to extend over and engage the box side wall and resilient means arranged to press and hold the inwardly concaved portions of the box side walls against the side wall portions of the form block.

19. Apparatus for making boxes having inset end walls, including in combination, an upper form block adapted to be passed interiorly into a box, a portion adapted to extend over and engage the box side wall means for retaining the box in position on said form block, and a lower form block adapted to telescope the box end wall into the box side wall. 5
20. Apparatus for making boxes having inset end walls, including in combination, an upper form block adapted to be passed interiorly into the box, a lower form block adapted to telescope the box end wall into the box side wall, and means extending from the top of said box side wall for pressing and holding the box side wall against the lower form block. 10
21. Apparatus for making boxes having inset end walls, including in combination, an upper form block adapted to be passed interiorly into the box, a lower form block adapted to telescope the end wall of the box into the side wall thereof, and adjustable means overhanging the top of the box side wall for pressing and holding the box side wall against the lower form block. 15
22. Apparatus for making boxes having inset end walls, including in combination, an upper form block adapted to be passed interiorly into the box, means for retaining the box in position on said form block, and an adjustable plate member overhanging the top of the box side wall for pressing and holding the box side wall against the lower form block. 20
23. Apparatus for making boxes having inset end walls, including a lower form block having a raised center portion and a recessed rim portion, said center portion being adapted to telescope the box end wall into the side wall thereof when the side wall is fitted within said recessed rim portion and means overhanging the top edge 25 of the box side wall for retaining the lower edge thereof seated within said recessed rim portion. 30
24. Apparatus for making boxes having inset end walls, including in combination, an upper form block adapted to be passed interiorly into the box, a lower form block having a raised center portion and a recessed rim portion, said center portion being adapted to telescope the box end wall into the side wall thereof, and adjustable means overhanging the upper form block 35 adapted to press and hold the lower edge of the box side wall within and against said recessed rim portion. 40
25. Apparatus for making boxes having inset end walls, including in combination, an upper form block adapted to fit within the box and shaped to conform to the inside surface of the box side walls, means for retaining the box in position on said form block, and a lower form block having a raised center portion and a recessed rim portion, said center portion being adapted to telescope the box end wall into the side wall thereof when said form blocks are manipulated. 45
26. Apparatus for making boxes having inset end walls, including in combination, an upper form block adapted to fit within the box and shaped to conform to the inside surface of the box side walls, means for retaining the box in position on said form block, a lower form block having a recessed rim portion and a raised center portion, said center portion being adapted to telescope the box end wall into the side wall thereof, and adjustable means overhanging the upper form block adapted to press and hold the lower edge of the box side wall within and against 50
- said recessed rim portion when said form blocks are manipulated. 55
27. Wrapping machine structure for folding portions of a wrap sheet against a box side wall including a member arranged in inclined position with respect to the lower edge of the box side wall and operative to progressively wipe portions of the wrap against the box side wall. 60
28. Wrapping machine structure for folding portions of a wrap sheet against a box side wall including, a member positioned on an incline with respect to the lower edge of the box side wall and operative to progressively wipe said wrap portions in overlapping relationship against the box side wall. 65
29. Wrapping machine structure for folding portions of a wrap sheet against the side walls of a box including a plurality of wiping members surrounding the box and arranged in inclined position with respect to the lower edge of the box, 70 said members being operative to progressively wipe portions of the wrap in overlapping relationship against the box side wall. 75
30. Apparatus for wrapping the arcuate side wall of a box including a wiping member inclined with respect to the lower edge of said side wall, said member being operative to progressively wipe the tab portions of the wrap sheet upwardly against the side wall in overlapping relationship. 80
31. Apparatus for wrapping boxes having arcuate side walls including wiping brushes of arcuate shape arranged in inclined relationship with respect to said arcuate side walls, said brushes being operative to progressively wipe tab portions of the wrap sheet upwardly against the side walls in overlapping relationship. 85
32. Apparatus for wrapping heart-shaped boxes including in combination, a pair of wiping members of arcuate shape arranged to wipe portions of the wrap against the side walls of the box progressively from the tip of the box to the base end thereof, said members being inclined with respect to the bottom of the box. 90
33. Apparatus for wrapping boxes having arcuate side walls, including wiping members arranged in inclined relationship with respect to said side walls, said members being operative to progressively wipe tab portions of the wrap in overlapping relationship against said side walls, and clamping members shaped to conform to the side walls of the box adapted to move inwardly and firmly press the glued tab portions into adhesive contact with the box side walls. 95
34. Apparatus for making boxes having padded end walls including in combination, a lower form block having a concave top portion shaped to conform to the desired padded contour of the box end wall, and an upper forming block adapted to press the end wall, the padding and wrap sheet against the lower forming block to cause said box parts to adhesively adhere to one another. 100
35. Apparatus for making boxes having padded end walls including in combination, an upper form block shaped to conform to the side wall contour of the box, and a lower form block having a concave top portion shaped to conform to the desired padded contour of the box and adapted to receive the padding material and wrap sheet thereon, said upper block being adapted to press the box end wall into adhesive engagement with said padding and wrap sheet. 105
36. Apparatus for making boxes having padded end walls including a lower form block having a concave top portion and a raised outer portion surrounding the concave portion, said concave 110

portion being shaped to conform to the desired padded contour of the box end wall.

37. Apparatus for making boxes having padded end walls including an upper forming block shaped to conform to the side wall contour of the box, and a lower forming block having a concave center portion and a raised outer portion sur-

rounding the concave portion, said concave portion being shaped to conform to the desired padded contour of the box end wall, said blocks being operative to shape the padding on said end wall and to cause the wrap sheet to adhere to the end wall at the unpadded parts thereof.

GIDEON R. KREIDER, JR.
